UNITED STATES PATENT OFFICE.

GEORGE C. SHORT AND WILLIAM L. ROE, OF NEW LONDON, CONN., ASSIGNOR
OF ONE-FOURTH TO ALBERT G. DAVIDSON, OF SAME PLACE.

CAR-COUPING.

SPECIFICATION forming part of Letters Patent No. 286,492, dated October 9, 1883.

Application filed August 31, 1883. (No model.)

To all whom it may concern:

Be it known that we, G. C. SHORT and W. L. ROE, citizens of the United States, residing at New London, in the county of New London and State of Connecticut, have invented certain new and useful Improvements in Car-Couplers, of which the following is a specification, reference being had therein to the accompanying drawings.

10 Our invention has relation to improvements in car-couplers; and the object of the device is to provide an automatic coupling for railway-cars, simple in construction and reliable and efficient in operation; and the novelty consists in the construction of the same, as will be hereinafter more fully described.

In the accompanying drawings similar letters of reference indicate the same parts of the invention.

20 Figure 1 is a view of the coupler in position for coupling. Fig. 2 is a similar view coupled; and Fig. 3 is a perspective view of the slide removed from the draw-head.

A is the draw-head, and its forward end is 25 provided with a cap, B, hinged at C.

D is a detachable pin in the body of the draw-head, which projects through an opening, c, in the cap B when the latter is closed, and it is provided with an eye, a, to facilitate 30 its removal from the top or sides of the car in uncoupling.

E is a slide, consisting of the carriage F, having recess G, and the guide-rods H H' and the follower I. This slide is mounted in the 35 forward end of the draw-head A, and has a limited end-play. The cap B is thrown back, as shown in Fig. 1, and the link K is laid against it, with its lower end resting in the recess G of the carriage F, which has been pulled 40 forward so its follower I projects beyond the face of the draw-head. As the cars come together the follower is struck first, which pushes

the carriage back, causing the link to fall forward over the pin D on each draw-head, and the concussion at the same time throws the 45 caps down, securely coupling the cars, as shown in Fig. 2. To uncouple, the pin D is raised and the link freed, thereby releasing the cars.

i i are guides on the inner side of the cap, 50 to hold the link in position when elevated, and e e are grooves in the draw-head A, to allow the depression of the link when coupling with cars of different heights.

In case the pin D is lost, any coupling-pin 55 can be used that will pass through the opening c in the cap B.

Having thus described our invention, what we claim as new and useful is—

1. The draw-head A, having slide E and pin 60 D, in combination with the link K, as and for the purpose set forth.

2. The draw-head A, having hinged cap B, with opening c, the slide E, and removable pin D, in combination with the link K, as set forth. 65

3. The draw-head A and slide E, having carriage F, provided with recess G, the removable pin D, and cap B, in combination with the link K, as and for the purpose set forth.

4. The draw-head A, slide E, removable pin 70 D, and hinged cap B, having guides i i, in combination with the link K, as set forth.

5. The combination, with the draw-head A, pin D, and link K, of the slide E, consisting of the follower I, guide-rods H H', and carriage F, having recess G, as and for the purpose set forth. 75

In testimony whereof we have affixed our signatures in presence of two witnesses.

GEORGE C. SHORT.
WILLIAM L. ROE.
